US00D856766S

(12) **United States Design Patent** (10) **Patent No.:** **US D856,766 S**
(45) **Date of Patent:** **** Aug. 20, 2019**

(54) **OSCILLATING SAW BLADE**

- (71) Applicant: **BLACK & DECKER, INC.**, New Britain, CT (US)
- (72) Inventors: **Thomas R. Kaye, Jr.**, Bel Air, MD (US); **James R. Niblett**, Columbia, MD (US)
- (73) Assignee: **BLACK & DECKER INC.**, New Britain, CT (US)
- (**) Term: **15 Years**
- (21) Appl. No.: **29/664,698**
- (22) Filed: **Sep. 27, 2018**

Related U.S. Application Data

- (60) Division of application No. 29/525,056, filed on Apr. 27, 2015, now Pat. No. Des. 832,666, which is a continuation of application No. 29/447,173, filed on Mar. 1, 2013, now abandoned, which is a continuation-in-part of application No. 13/385,614, filed on Jul. 16, 2012, now Pat. No. 9,073,195.

CLAIM

The ornamental design for an oscillating saw blade, as shown and described.

DESCRIPTION

FIG. 1 is a perspective view of an oscillating saw blade. FIG. 2 is a left view of the oscillating saw blade of FIG. 1. FIG. 3 is a right view of the oscillating saw blade of FIG. 1. FIG. 4 is a front view of the oscillating saw blade of FIG. 1. FIG. 5 is a rear view of the oscillating saw blade of FIG. 1. FIG. 6 is a top view of the oscillating saw blade of FIG. 1; and, FIG. 7 is a bottom view of the oscillating saw blade of FIG. 1.

The broken lines in the drawings illustrate portions of the oscillating saw blade and form no part of the claimed design.

1 Claim, 5 Drawing Sheets
